CURTAIN STRETCHER

Matilda C. Boyer, Pittsburgh, Pa.

Application February 21, 1933. Serial No. 657,910

4 Claims. (Cl. 45—24)

The invention relates to a curtain stretcher and more particularly to an adjustable curtain stretcher.

The primary object of the invention is the provision of a stretcher of this character, wherein in its frame is made up with a plurality of sections and a series of blocks, these being variably grouped to increase or decrease the size of the frame when set up for use, thereby adapting the frame correspondingly to the size of the article, such as a lace curtain, to be stretched, the range of adjustment being great so that either the smallest or the largest curtain can be stretched thereon.

Another object of the invention is the provision of a stretcher of this character, wherein the blocks constituting parts of the frame thereof are carried upon a cord or cable, thus holding the blocks intact and enabling the convenient introduction or removal of the same to and from place without liability of the loss of any of the blocks of the series.

A further object of the invention is the provision of a stretcher of this character, wherein the sections and blocks constituting the frame thereof are readily separable so as to permit the collapsing of the stretcher when not in use and its storage in the least possible space.

A still further object of the invention is the provision of a stretcher of this character which is extremely simple in construction, compact, thoroughly reliable and efficient in its purpose, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a plan view of a curtain stretcher constructed in accordance with the invention and set up to the maximum range thereof.

Figure 2 is a fragmentary perspective view of the frame of the stretcher showing the blocks of a series partly placed and the stringing of such blocks in accordance with the invention.

Figure 3 is a plan view of one of the keys of the frame.

Figure 4 is an enlarged perspective view of one of the blocks of the frame.

Figure 5 is a perspective view of one of the supporting legs for the frame of the stretcher.

Similar reference characters indicate corresponding parts throughout the several views in the drawing.

Referring to the drawing in detail, the curtain stretcher comprises a substantially rectangular-shaped frame A including L-shaped corner pieces 10, the side and end pieces 11 and 12 respectively and the separable series of blocks 13 in association with the side and end pieces 11 and 12 respectively.

The corner pieces 10, side and end pieces 11 and 12 and the blocks 13 at one side of the frame, close to the inner margin thereof, carry pins 14 with which engages the article, such as a lace curtain, to be stretched, so that in this manner the article is carried by the frame of the stretcher.

Slidably fitted through suitable bores in the corner pieces 10 are substantially U-shaped keys 15, each being made from a single length of rigid wire bent on itself into the U form. These keys 15 in each corner piece 10 are removably fitted therein at right angles to each other, or substantially so, and the inner ends of the tines 16 of these keys are received in suitable bore-like sockets formed in the side and end pieces 11 and 12 as is clearly shown in Figure 2 of the drawing so that a collapsible and adjustable frame will be set up.

The blocks 13 of each series have the holes 17 for accommodating the tines 16 of the keys 15 and one or more or the entire number of the series of blocks 13 can be engaged with the keys. Thus these blocks will constitute fillers to increase or decrease the size of the frame of the stretcher according to that size desired corresponding to the size of the article to be stretched thereon.

Each series or group of blocks 13 is loosely strung upon a cord or cable 18 which is threaded through suitable apertures 19 midway of the blocks. The cord or cable 18 at opposite ends has formed terminal loops 20, either one of which is engageable with a keeper hook 21 on each of the corner pieces 10 as is clearly shown in Figure 100 2 of the drawing and in this fashion the strung group or series of blocks is anchored with its companion corner piece. In this manner the loss of the blocks or the misplacing thereof is avoided and on the assembly of the frame of the stretcher the series of blocks are intact therewith.

Mounted at the outer side of the end branches of the corner pieces 10 are strap-like socket members 22, each being adapted to accommodate the tongue 23 of a prop or leg 24 so that the latter 110

can be detachably connected with the frame of the stretcher and in this fashion the said stretcher can be supported by the legs elevated from the ground or foundation and thus eliminate the touching of the article held upon the frame of the stretcher when in use, with the ground or foundation.

The corner pieces 10 and the side and end pieces 11 and 12 have in their upper faces clearance notches 25 at their extremities, these being for the cords or cables 18 so as to avoid a separation of the blocks 13 next to the extremities of said pieces by such cords or cables, causing a spreading of these blocks and pieces. In other words, the notches 25 will accommodate the cords or cables so that the blocks 13 next to the extremities of the pieces 10, 11 and 12 can come together or in contacting relation without interference by said cords or cables as should be obvious.

What is claimed is:

1. A stretcher of the character described comprising an adjustable frame including L-shaped corner pieces, side and end pieces and series of blocks, and keys removably inserted in the corner pieces and engageable in the side and end pieces and detachably supporting the series of blocks.

2. A stretcher of the character described com-

prising an adjustable frame including L-shaped corner pieces, side and end pieces and series of blocks, keys removably inserted in the corner pieces and engageable in the side and end pieces and detachably supporting the series of blocks, 80 and anchoring pins on the corner pieces, side and end pieces and blocks.

3. A stretcher of the character described comprising an adjustable frame including L-shaped corner pieces, side and end pieces and series of blocks, 85 keys removably inserted in the corner pieces and engageable in the side and end pieces and detachably supporting the series of blocks, anchoring pins on the corner pieces, side and end pieces and blocks, and flexible elements having 90 loosely strung thereon the said blocks.

4. A stretcher of the character described comprising an adjustable frame including L-shaped corner pieces, side and end pieces and series of blocks, 95 keys removably inserted in the corner pieces and engageable in the side and end pieces and detachably supporting the series of blocks, anchoring pins on the corner pieces, side and end pieces and blocks, flexible elements having loosely strung thereon the said blocks, and means on the 100 corner pieces for the detachable connection of either end of the flexible elements therewith.

MATILDA C. BOYER.
